UNITED STATES PATENT OFFICE.

FREDERICK J. WOOSTER, OF WATERBURY, CONNECTICUT.

PUZZLE.

SPECIFICATION forming part of Letters Patent No. 432,589, dated July 22, 1890.

Application filed May 13, 1889. Serial No. 310,615. (No model.)

To all whom it may concern:

Be it known that I, FREDERICK J. WOOSTER, of Waterbury, in the county of New Haven and State of Connecticut, have invented a new 5 Improvement in Puzzles; and I do hereby declare the following, when taken in connection with accompanying drawings and the letters of reference marked thereon, to be a full, clear, and exact description of the same, and 10 which said drawings constitute part of this specification, and represent, in—

Figure 1, a top view; Fig. 2, a vertical central section of the same; Fig. 3, a modification in the shape of the surface of the table.

15 This invention relates to an improvement in that class of puzzles which consist of a table having one or more marbles or balls free to revolve thereon, the puzzle being to locate such one or more balls at a predetermined 20 point.

The object of the invention is a puzzle to employ a single marble or ball, and which, while possible to be accomplished, presents considerable difficulty to such accomplishment; and it consists in a bed or table, the 25 surface of which is of convex shape, having a rim around its edge, the center or apex having a cavity formed therein of a size sufficient to locate a marble when it shall reach that 30 cavity, and as more fully hereinafter described.

The table A is preferably of circular shape, and around its edge is a rim B. The surface of the table A is made of substantially convex shape, and in the center or apex a cavity a is 35 formed, which is adapted to receive a marble or ball, which is to be employed. b, Fig. 2, represents the ball. The convex surface gives to the ball or marble an inclination to the outside of the table. A rotary motion of the 40 ball around the table also gives under cen-

trifugal force a tendency of the ball to the outer edge of the table.

The puzzle is to locate the marble or ball in the center, as indicated in broken lines, Fig. 2, and owing to the natural tendency of 45 the ball to fly away from this cavity the lodgment of the ball in the center is very difficult to accomplish.

While I prefer to make the surface of the table convex, it may be made of conical shape, 50 as seen in Fig. 3, and accomplish the same result—that is, the natural tendency of the ball away from the central cavity. By the term "convex surface," therefore, I wish to be understood as embracing any surface having 55 a general inclination from the central cavity outward. The rim B is employed only as a protection to prevent the escape of the ball.

I claim—

1. A toy or game, the same consisting of a 60 box whose bottom is convex and smooth and is provided with a central depression, and a ball adapted to travel upon the bottom of said box, the whole adapted to be held in the hand and manipulated to different planes, substan- 65 tially as set forth.

2. A device of the character described, the same consisting of a circular rim, a concavo-convex plate arranged within said rim and having a central depression adapted to form 70 a resting-place for the spherical object, but otherwise smooth and unobstructed, and a ball larger than said depression and adapted to move over the surface of the plate, the whole adapted to manipulation by the hand, as 75 specified.

FREDERICK J. WOOSTER.
